UNITED STATES PATENT OFFICE.

PHILO F. TERRY, OF GREEN CITY, MISSOURI.

HAY-STACKER.

SPECIFICATION forming part of Letters Patent No. 315,185, dated April 7, 1885.

Application filed October 31, 1884. (No model.)

To all whom it may concern:

Be it known that I, PHILO F. TERRY, of Green City, in the county of Sullivan and State of Missouri, have invented a new and Improved Hay-Stacker, of which the following is a full, clear, and exact description.

The object of my invention is to facilitate the stacking of hay, grain, or other substances.

10 The invention consists in certain mechanism whereby the loaded carrier is drawn up the inclined track and the load is automatically discharged onto the stack, and the apparatus adjusts itself for the descent of the carrier for the next load.

15 The invention consists, also, in special constructions of the carrier for securing its load and advantageously applying the draft to it, and also in the connections of the track-frame to the base-frame to allow the track-frame to be raised or lowered at its back end to facilitate transportation of the stacker and to level the track-frame transversely at the lower end and alter the pitch or incline of the 20 track-frame to insure the smooth travel of the carrier on it, all as hereinafter fully described and claimed.

25 Reference is to be had to the accompanying drawings, forming part of this specification, in which similar letters of reference indicate corresponding parts in all the figures.

30 Figure 1 is a plan view of my improved hay-stacker. Fig. 2 is a side elevation, drawn to a larger scale, of the hay-carrier, with portions of the base and track beams. Fig. 3 is a side elevation of the stacker, drawn to the same scale as Fig. 1. Fig. 4 is a central sectional side elevation of the upper part of the 35 hay-stacker, showing the carrier in position for discharging its load; and Fig. 5 is an inside perspective view of the roller-supporting plate or block held at the forward end of the side bars of the carrier.

35 The letter A indicates the base or bed frame of the stacker, the side bars *a* of which frame are rounded at the ends, so as to form sled-runners, on which the stacker may be drawn to and from the place of use.

40 B is a frame which is pivoted at *b*² to the bed-frame A, and is fastened at the upper or outer ends of its side bars *b* to the side bars *c* of the track-frame C of the stacker by bolts *c*²

or other fastenings, which may be removed to allow the frame B to be folded down in line with the bed-frame A, and the track-frame bars *c* are connected pivotally at their rear ends by levers D to the side bars of the bed-frame A, so that the track-frame C may be folded down on top of the frames A B to facilitate transportation of the stacker and economize room in housing the stacker when it is out of use. The opposite side bars *a a* of the bed-frame A are shown tied together by cross bars or braces *a'*, the side bars *b b* of frame B by braces *b'*, and the side bars *c c* of track-frame C by cross-bars *c'*; but the frames A B may have any approved construction.

45 At the upper forward end of the frame C, I fasten the bars E E, one at each side, and between these bars I pivot on gudgeons *f*² the swinging or dumping frame F, the end joints between the side bars *c c* of frame C and the side bars *f f* of frame F being inclined, or diagonal or otherwise shaped, so that when the frame F swings back after dumping the 50 load from the hay-carrier the joints will hold the frames F C in line to cause the hay-carrier tracks F', fixed on frame F, to meet the tracks C' on frame C, to allow the carrier to descend for another load, as will be hereinafter more 55 fully explained.

50 I show the side bars *f f* of frame F tied together by cross-bars *f'*, to which are fastened the plates or keepers *g g*, in which a bolt, G, works, and so as to enter a striking 60 plate or socket, H, fixed on a cross-bar, *h*, fastened to the opposite side bars *c c* or E E, for locking the dumping-frame F in line with the track-frame C, as in full lines in Fig. 3.

55 On the bolt G is placed the spring *g'*, which 65 presses against the bolt-collar *g*² for automatically engaging the bolt with the plate H as the frame F is swung back into line with the frame C by the weight I, to which is connected a cord, J, which passes over guide-pulleys *i j* 70 on the frames B C, respectively, and up over the upper side of the dumping-frame F, and is connected at *j'* with one of the cross-bars of said frame, as will readily be understood.

65 The letter K indicates the hay-carrier, which 75 I make in two sections, K' K². The front or main section, K', is made with a cross-bar, L, having a number of bars, *l*, fixed to it at suitable distances apart to form a rack to receive

and hold the hay. The opposite side bars L' L' of the carrier-section K' are made heavier than the rack-bars l, and are firmly bolted to the cross-bar L, which latter bar has 5 gudgeons or pins L², one at each end, on which pins the main wheels M of the carrier K are journaled. The gudgeons L² project sufficiently beyond the carrier-wheels M to engage or enter upturned hooks N N, fixed to 10 the lower ends of the track-frame side bars c c, also the upturned hooks O O, fixed on the upper faces of the side bars f f of the dumping-frame F, and about over its center of oscillation, and to enter, also, the upturned hooks 15 P P, fixed to the ends of the stationary side bars E E, and for purposes hereinafter described.

To the forward ends of the opposite side bars L' L' are journaled the forward rollers or 20 wheels, Q, which run against the outer faces of the track-bars C' F', and the upper and lower roller-wheels, R S, which run against the upper and lower edges of the track-bars, the wheels R being made quite large and 25 heavy, as they serve, with the wheels M, to bear the weight of the carrier and its load.

As shown in Fig. 5, I prefer to journal the pilot-wheels Q R S to pins or gudgeons held to metal plates or blocks T, to be bolted to the 30 ends of the bars L', and on the plates T, I fix curved plates t, which extend over the wheels R, and guard the wheels from the hay, which otherwise might fall on them and obstruct the travel of the carrier.

35 The section K² of the carrier K is made with a cross-bar, L³, to which the rack-bars l' are attached about in line with the rack-bars l of the section K', and the two side bars L⁴ L⁴ of section K² are made quite heavy, and are pivoted at k to the side bars L' L' of the carrier-section K', to hinge the two carrier-sections to each other.

40 L⁵ L⁵ are bars or links, which are pivoted at k' to the bars L⁴ of section K², and connect by slots k² in the links and pins k³ in the bars L' with the section K'. The slots k² allow the two carrier-sections to lie in the same plane for receiving their load, as in Fig. 3, and also allow the section K² to be swung up forward 45 on the pivots k, as in Fig. 2, to prevent the falling of the hay from the carrier as it is hauled up the inclined track-frame C to be dumped on the stack.

45 U U are levers, which are pivoted at u to the side bars L' of section K', and are connected pivotally at u' with the forward ends of links V, which have slots v at their other ends working over or on pins v', fixed to the bars or links L⁵. The slots v allow the levers U to 50 drop down by the side of the bars L⁵, as in Fig. 3, so that the levers do not obstruct the free passage of hay onto the carrier, and also allow the carrier-sections to assume the same plane and allow section K² to swing upward, and by 55 contact of the back ends of these slots with the pins v' and contact of the back ends of slots k² with the pins k³ draft is applied to

the carrier to haul it up the track-frame C by means of ropes or chains W W, which are connected to the upper ends of the levers U U, 70 and pass forward and upward and over pulleys w w, journaled at the outer end of the dumping-frame F, and thence downward and backward through guide eyes or pulleys x x to the rear of the machine, and within reach of the attendants who load the hay onto the carrier. The draft-ropes W may lead to any point at or from which power may advantageously be applied by hand or by horse-power or other motor to elevate the carrier, which 80 has prongs or teeth l', fixed to the forward ends of the carrier-bars l, to prevent the hay from going clear over when drawn or pushed onto the carrier. A suitable trip-bar or projection, X, is fixed to the under side of the hay-carrier, preferably to its cross-bar L, and in position to strike the upturned end G' of the bolt G, for releasing the platform F automatically to dump the hay from the carrier onto the stack. 85

90 As before stated, the levers D D serve to pivot the track-frame C to the bed-frame A, the connection being made by pivot-pins d d' passed through each lever into the track and bed-frames, respectively; but the levers D also allow the lower end of the track-frame C to be lifted clear of the ground while the stacker is being drawn to a new place, and also to permit one or both side bars of frame C to be adjusted vertically by the levers to level the 95 lower end of the frame transversely on uneven ground and set the tracks "out of wind," and also to alter the pitch or grade of inclination of the track-frame, so that the hay-carrier may travel smoothly on it. 100

To lock the levers D at different elevations of the track-frame, pins d² may be passed into any one of a series of holes, d³, in said frame C, or into any one of a series of holes, d⁴, in the bed-frame A, when the free ends of the 110 levers are depressed, the lock-pins d² standing above the levers to hold the lower end of the track-frame in position, as illustrated in Figs. 1 and 2. The levers D also may have a series of holes, as at d⁵, through any one of which 115 the fulcrum-pins d' may be passed. A wide range of vertical adjustment thus is secured for the track-frame for purposes above stated.

The operation is as follows: The stacker 120 having been drawn to the desired position, the hay or other substance to be stacked is drawn or pushed onto the carrier K by horse or hand rakes, or otherwise, the carrier then resting by its gudgeons L² in the hooks N, and the carrier-sections K' K² then lying flat in the same 125 plane. The ropes W then are drawn upon and act first to carry the levers U, links V, and bars L⁵ forward, to swing the section K² forward, as in Fig. 2, which carries the rear ends of the slots v k² against the pins v' k³, to 130 limit the forward swing of the section K² and bring the levers U into positions to apply the draft of ropes W advantageously to elevate the loaded carrier to the upper end of frame

C, at which place the gudgeons L² will enter the hooks O of the dumping-frame F, and at the same time the bar X will strike the end G' of bolt G to withdraw it from the plate H, 5 and allow the frame F to swing forward on its pivots f² and tilt the carrier K, as in Fig. 4, to discharge its load onto the stack below. As the dumping-frame F and carrier K swing over, the gudgeons L² of the carrier are caught 10 in the hooks P to limit the down swing of the dumping-frame and carrier. The load having been discharged on the stack, the weight I now acts to swing the dumping-frame back into line with the track-frame C, and the carrier K is ready to descend for its next load. 15

Having thus described my invention, what I claim as new, and desire to secure by Letters Patent, is—

1. In a hay-stacker, the carrier track-frame 20 made with carrier-retaining hooks P at the upper end of its main portion, and with a pivoted dumping-section at the upper end provided with hooks O, in combination with projecting pins or gudgeons on the carrier 25 adapted to enter the hooks O P, substantially as shown and described.

2. In a hay-stacker, the carrier track-frame made with carrier-retaining hooks P at its upper end, hooks N at its lower end, and a pivoted dumping-section, F, at its upper end, 30 having hooks O, in combination with projecting pins or gudgeons on the carrier adapted to enter the hooks, substantially as shown and described.

3. In a hay-stacker, the combination of the carrier track-frame made with hooks P, and a pivoted dumping-section, F, at its upper end, a bolt, G, having a projection, G', by which said section is held in line with the 40 main-track section, hooks O on the dumping-frame F, pivots or gudgeons L² on the carrier engaging the hooks O P, and a trip-bar on the carrier adapted to draw the bolt to allow the dumping-frame and carrier to swing for 45 discharging the load, substantially as shown and described.

4. In a hay-stacker, the combination of the carrier track-frame made with hooks P, a pivoted dumping-frame, F, at its upper end, 50 means for latching the frame F in line with the main-track section, and means for releasing it automatically by the advance of the carrier, substantially as specified, combined

with a suspended weight connected to the dumping-track section to swing it backward 55 when the load is discharged from the carrier, substantially as shown and described.

5. In a hay-stacker, the combination, with the track-frame C, hooks P, and a catch H, the pivoted track-section F, a slide-bolt, G, 60 having an upturned end, G', and hooks O, of the trip-bar X on the carrier, and weight and cord I J, substantially as shown and described.

6. In a hay-stacker, the combination of the carrier K, made in two sections, K' K², hinged 65 together at k, and slotted connecting-bars L⁵, means for supporting the carrier to run on the track-frame, and means for drawing the carrier up the frame, substantially as shown and described. 70

7. In a hay-stacker, the carrier K, made in two sections, K' K², hinged together at k, and slotted connecting-bars L⁵, in combination with the levers U, pivoted to sections K' at u, and loosely connected to said bars L⁵, the pins v', 75 and the draft-ropes W, substantially as shown and described.

8. In a hay-stacker, the carrier K, made with rear wheels, M, pilot-wheels Q, running on the inner faces of the track-bars, and wheels R S, 80 running on the top and bottom edges of the track-bars, substantially as shown and described.

9. In a hay-stacker, the combination of a track-frame, C, having an upper dumping-section, F, a carrier, K, made in two sections, K' K², hinged to each other, connecting-bars L⁵, levers U and links V, draft-ropes W, connected to levers U, and passing over the outer ends of the dumping-section F, a spring-pressed bolt, G, a trip-bar on the carrier, and a suspended weight, I, connected to the dumping-frame F, the whole constructed and combined to operate substantially as shown and described. 90 95

10. In a hay-stacker, the track-frame C, the base-frame A, levers D, pivoted at d d' to the track and base frames, respectively, in combination with means for locking the levers in different positions, substantially as shown and described. 100
